CLAIM

The ornamental design for a waving wooden flag sculpture, as shown and described.

DESCRIPTION

FIG. 1 is a front perspective view of a waving wooden flag sculpture showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top elevation view thereof;

FIG. 7 is a bottom elevation view thereof;

FIG. 8 is a perspective view thereof showing the middle portion partially open to reveal the frame and compartment behind;

FIG. 9 is a perspective view thereof showing the middle portion fully open to reveal the frame and compartment behind;

FIG. 10 is a bottom elevation view thereof with the middle portion fully open;

FIG. 11 is a top elevation view thereof with the middle portion fully open;

FIG. 12 is a front elevation view thereof with the middle portion fully open; and,

FIG. 13 is a perspective view thereof showing the middle portion fully open to reveal the frame and compartment behind.

1 Claim, 10 Drawing Sheets
